UNITED STATES PATENT OFFICE

WILLIAM E. WINE, OF TOLEDO, OHIO

CAR LADDER

Application filed April 16, 1928. Serial No. 270,303.

My invention relates to new and useful improvements in ladders, and although especially designed for use on freight cars, it will be readily apparent that the same may be used on other structures wherever a metal ladder is desired.

One of the objects of the present invention is to produce an all-metal ladder comprising stiles made out of angle iron with the holes in the opposite faces of each angle iron so that after the rungs are placed in position and the stiles set, no further fastening for the rungs is necessary.

In its broadest aspect it is similar to the ladder shown in the patent granted to me on February 13, 1917, and numbered 1,215,455.

The present application also shows and describes briefly the manner in which ladders are to be fastened to cars but this feature is shown and described more in detail and claimed in a divisional application, filed by me on April 17th, 1929.

Still another object of the invention is to provide a ladder the stiles of which are made of angle iron and rather than make circular holes in the faces of the angle, rectangular openings are provided so that relatively thick rungs may be used that have their ends slightly flattened and may thus fit within the openings, that may be smaller than if round openings were provided.

Still another object of the invention is to provide a ladder, the stiles of which are provided with openings, the sides of the openings being flattened to receive cooperating rungs with flattened ends and thus secure the rungs more rigidly in position than would be possible if simply round openings were used in the stiles to receive round end rungs.

With these and other objects in view, the invention consists in certain new and novel arrangements and combination of parts as will be hereinafter more fully described and pointed out in the claims.

Referring now to the drawings showing a preferred embodiment of the invention,

Fig. 1 is a fragmentary side elevation of a car showing a ladder on the side of the car and a ladder on the end of the car,

Fig. 2 is an end elevation showing the two ladders in place,

Fig. 3 is a fragmentary enlarged lower end view of one of the stiles, showing a part of a rung and the fastening means for the stiles,

Fig. 4 is a sectional view taken on line 4—4 of Fig. 3,

Fig. 5 is a similar view, the bracket and rung being left out for the sake of clearness,

Fig. 6 is a horizontal sectional view, one-half being taken through the bracket, and the other half being taken through the rung,

Fig. 7 is a perspective view of the lower end of the stile,

Fig. 7a is a perspective view of the bracket cooperating with the lower end of the stile, and

Fig. 8 is a fragmentary perspective view taken from the outer corner of the stile.

Referring more in particular to the several views, there is shown in Fig. 1, the fragmentary end 1 of a hopper car, and secured by brackets, (to be hereinafter briefly described,) is the ladder 2 which extends from the top of the car down to the side sill 3.

There may also be seen a ladder 4 fastened to the end of the car, while beneath the ladder 2 may be seen the usual step 5. It will also be seen that the ladder comprises the two stiles 6 and 7, which are identical, so a description of the one will be a description of the other.

Describing, therefore, in detail one of these stiles there will be seen a metal angle iron which is provided in the present illustration, with five sets of holes in the two faces, one hole of each set being opposite the hole of the other.

In Fig. 7, a set of these holes may be seen and one in the one face of the angle and the other hole in the opposite face.

In my earlier patent, above referred to, I simply made these holes circular in shape, but I have found that by flattening out the sides 9 of the openings I accomplish two functions that I did not accomplish in my earlier construction.

Looking for the moment at Fig. 8, there is shown a fragmentary portion of a rung

10, the offset or bend coming at the point 11 and at this point the rung is slightly flattened as at 12, the rung again being bent as at 13, and projecting outwardly as at 14 while the 5 front and rear faces of the ends are also flattened as at 15, and 15a. The face 15a is also inclined to the axis of the rung so that it will clear the flattened side wall 9 of the opening as the rung is inserted.

10 To insert this rung 10, it is simply placed in the opening in one face of the angle and then moved slightly inwardly until the end 14 passes through the other hole 9 as will be readily understood.

15 After the rungs are inserted in one of the stiles, the opposite stile is placed with its row of holes opposite the rung ends and then the stile is turned so that the rung ends may pass through the holes in the opposite face of 20 the stile, and we then have all of the rungs tightly locked in position, with reference to the two stiles.

By flattening the opposite ends of the rung, and by making the sets of holes rectangular 25 in shape, it allows me to use a thicker rung without drilling larger holes in the stile.

Secondly, the rung is held more tightly in position as the flattened faces of the openings will bear along the flattened faces of the 30 rung and thus provide against any turning movement of the rung.

Of course, it is desirable to drill as small holes as possible in the stiles as the larger the hole the greater the loss in strength of the 35 stile while, on the other hand, it is desirable to use say rungs of $\frac{3}{4}$ " diameter, rather than the thinner rungs ($\frac{5}{8}$) that are in common use today. It goes without saying that it is desirable to have the rungs held as tightly as 40 possible against movement, as loose or broken rungs have caused many serious accidents.

The manner of passing the ends of the rungs through the two opposite faces of the 45 stiles is well shown and described in my earlier patent, and many hundreds of thousands of these ladders are now in use, but as mentioned before, the openings were circular, rather than circular with the sides 50 flattened.

Now the manner of applying the ladders to the cars or other structures forms the subject matter of a divisional application, filed by me on the 17th day of April, 1929, and this 55 subject matter, therefore, will just be set out briefly. It will be seen that each of the stiles 6 has two brackets 16 thereon, each of which comprises a piece of metal having the one face 17 bent over on itself to form the face 18 and which, when in place, forms the resultant space 19 to receive the end 20 of a car bracket 21. The bracket is riveted, as at 22, to the inner face of the stile.

The bracket 16 is cut away along its inner 60 edge, as at 23, in the same plane with the

lower edge 24 of the inner face 17 of the bracket. Below the rivet 22, there is a hole 25 opposite a hole 26 in the face of the stile, so that when the stile is placed in position as shown in Fig. 3, the end 20 of the bracket 70 will fit within the space 18 and the lip 27 on the end 20 of the car bracket 21 will fit in the cut-out portion 23 to thus hold the stile in position.

There are two of these car brackets 21, one 75 being placed near the upper part of the car and one down by the side sill, and it will be understood that there are two brackets 16 on each stile, one near the top and one near the bottom, so that when the ladder is placed in position, the brackets 16 will fit over the car brackets 21. Bolts 28 will then be passed through the stiles and the brackets 16 and through bolt holes 29 in the ends of the brackets 21 to thus hold the ladder to the car. The 80 bolts 28 will have square heads to fit up against the lips 27, as may be seen.

Thus it will be seen that after the brackets are securely riveted to the car sides or car ends, the ladder being previously assembled, 90 will simply be placed slightly above the brackets and then pulled down into place so that the hooks will also engage the respective ends of the brackets, after which the bolts 28 will be tightened into position.

If at any time it is desired to remove the ladder, the bolts 28 are simply removed and the ladder lifted slightly off the bracket and then bodily removed.

From the foregoing it will be seen that I 100 have provided a ladder wherein relatively large rungs may be used, as the ends are flattened to fit in openings in the stiles that have their sides flattened, and the rungs will be tightly held in position and against any turning movement. Furthermore, the ladder may be completely assembled, slipped over the bracket and securely bolted thereto, thus 105 making a rigid construction throughout.

By flattening out the side walls of the holes 110 in the stiles, flattening the ends of the rungs, and by inclining one of the two faces at each end of the rungs, I am able to utilize rungs of greater diameter for the size of the holes in the stiles than would be possible, if simply round rungs were used and round holes were formed in the stile.

Again, by constructing the ends of the rungs and forming the openings in the stiles, as shown, the rungs are far more rigidly locked within the stiles than they would be if simply round end rungs and round openings in the stiles were utilized.

The cooperating brackets will rigidly support the ladder and the bolts will tie the several parts strongly together. The ladder is relatively light and will be strong and efficient in service.

Many slight changes might be made with- 130

out in any way departing from the spirit and scope of the invention.

Having thus described my invention what I claim as new and desire to secure by Letters Patent is:—

5 1. A freight car ladder comprising angular stiles, said stiles having openings substantially rectangular in shape in the opposite faces of said stiles, and round rungs having flattened ends to be interlocked within the openings of the two respective faces in each of said stiles.

10 15 2. A metal car ladder comprising stiles formed of angle irons and having oppositely disposed openings in the respective faces of said angle irons, said openings being rounded on their upper and lower walls and flattened on their side walls, round rungs having offset ends and the front and rear faces of the 20 the ends of the rungs being slightly flattened to interlock within the openings in said stiles.

25 3. A freight car ladder comprising two angle iron stiles, each of said stiles having openings oppositely disposed in the respective faces of the stile, said openings each having rounded upper and lower edges and flat sides, round rungs having off-set ends and their ends being slightly flattened to pass through said openings and to interlock 30 therewith to rigidly hold the rungs when the stiles are in position.

35 4. A freight car ladder comprising two angle iron stiles, said stiles having openings therein, said openings being flattened at their sides, rungs having off-set ends and said ends being flattened on their two faces to interlock with the said openings, one of the flattened faces at each end of the rungs being inclined to the axis of the rung to freely 40 pass within said respective openings as the rungs are passed within its openings in the stiles.

45 5. A car ladder comprising stiles, each of said stiles being formed of an angle iron and having openings oppositely disposed in the respective faces of the stile and said openings being arcuate at their top and bottom and flat on their sides.

50 6. A car ladder comprising stiles, a rung having off-set ends, the extreme ends extending parallel to the axis of the rung, the said ends being round throughout their greater length and flattened at their extreme ends and the rear faces of the extreme ends 55 of the rung being inclined to the axis of the rung.

60 7. In a car ladder a round rung having off-set ends, the said ends being flattened and one of the flattened faces being inclined to the axis of the rung.

65 8. A car ladder comprising angular stiles each having openings in their opposite faces, said openings having flattened side walls, rungs having offset and flattened ends and one face of the flattened ends of each rung

being inclined to the axis of the rung so that the rung may be passed within said flattened openings and interlocked therewith when the stiles are in position.

9. A car ladder comprising angular stiles and round rungs, each of said stiles being provided with oppositely disposed openings in each of their faces, the said openings having flattened side walls and arcuate tops and bottoms and the distance between said side walls of the openings being less than the normal diameter of the rungs, said rungs being provided with flattened and offset ends to interlock with the walls of the said openings in the stiles.

10 In testimony whereof I affix my signature.
